(57) **CLAIM**

The ornamental design for a waterproof case for an insulin pump, as shown and described.

DESCRIPTION

FIG. 1 is an isometric view of a waterproof case for an insulin pump in a closed position;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another isometric view of a waterproof case for an insulin pump in an open position.

The broken line showing of environment in the drawings is included for the purpose of illustrating only and forms no part of the claimed design.
